Primary Examiner — Mitchell Siegel*(74) Attorney, Agent, or Firm* — Ohlant, Greeley, Ruggiero & Perle, L.P.**(57) CLAIM**

The ornamental design for an ice machine, as shown and described.

DESCRIPTION

FIG. 1 is a top perspective view of a display of an ice machine of the present disclosure;

FIG. 2 is a front view of the display of FIG. 1;

FIG. 3 is a rear view of the display of FIG. 1;

FIG. 4 is a top view of the display of FIG. 1;

FIG. 5 is a bottom view of the display of FIG. 1;

FIG. 6 is a first side view of the display of FIG. 1; and,

FIG. 7 is a second side view of the display of FIG. 1.

The broken lines shown in the drawings are directed to environmental structure or boundaries and are for illustrative purposes only; the broken lines form no part of the claimed design.
